UNITED STATES PATENT OFFICE.

GEORGE W. FENIMORE, OF LOS ANGELES, CALIFORNIA.

CALENDAR.

Application filed February 23, 1921. Serial No. 448,592.

To all whom it may concern:

Be it known that I, GEORGE W. FENIMORE, a citizen of the United States, and a resident of Los Angeles, in the county of Los Angeles and State of California, have invented new and useful Improvements in Calendars, of which the following is a specification.

This invention relates in general to calendars, and more particularly to perpetual calendars, and the main object is to provide a calendar embodying a plurality of relatively adjustable cards, or discs, having suitable insignia and characters thereon, whereby when said members are brought into certain relationship, the day of the month and the day of the week for any year within the range of the calendar and for any month in any year may be visibly indicated and ascertained by reference thereto.

Another object is to provide in a calendar of the character stated, means for ascertaining dates and for providing a calendar, or a schedule, of dates, for any month of any year within the range of the calendar, together with the simultaneous indication in connection therewith of the month subsequent to any selected month.

A still further object is to provide in a calendar of the character mentioned, means for simultaneously displaying calendars for any two sequential months and a suitable system of indices, including a scale of characters which have a definite relation to the number of days in the month and are adapted for manipulation by establishing certain definite relationships therebetween, for determining and ascertaining the proper relationship between any two sequential months so that the calendar for such months may be displayed in a proper sequence.

A further object is to provide a calendar having an envelope, or folder, in which the cards or discs, bearing the insignia may be suitably held for adjustment, and means for relatively adjusting said cards or discs for simultaneously displaying a scale of dates for two sequential months.

In the consideration of my invention, it will be understood that the arrangement of a calendar for any one year will be repeated each 28th year, with the exception of centesimal years, and this single exception does not obtain with the centesimal years which are divisible by four-hundred. It will further be understood that all months of the

year have either twenty-eight, twenty-nine, thirty, or thirty-one days, and it is an object of my invention therefore, to provide a calendar which may have a range of any number of years thereon prior or subsequent to a given year, in which the calendar schedule of dates for any two sequential months may be simultaneously displayed, regardless of the number of days in the months; means being also provided for obscuring the superfluous number of days on the calendar from view. Other objects may appear as the description progresses.

I have shown one practical embodiment of my invention in the accompanying drawing, in which:

Fig. 1 is a face view of my improved calendar.

Fig. 2 is a sectional elevation of the same, on line 2—2 of Fig. 1.

Fig. 3 is a sectional plane of the same on line 3—3 of Fig. 1.

Fig. 4 is a face view of the current month calendar card.

Fig. 5 is a face view of the succeeding month calendar card.

Fig. 6 is a face view of the weekly index card.

Fig. 7 is a face view of the monthly index disc.

Fig. 8 is a face view of the yearly index disc.

Fig. 9 is a face view of the index member for obscuring the superfluous days of the month.

The form of calendar shown in the said drawings is one particularly adapted to be hung upon the walls and is designed so as to be as flat as possible and of moderate size, of economical construction, simple in operation and easy of adjustment for quickly determining the dates of any year prior or subsequent to a given date.

It will be understood that while the form shown in the drawing is preferred, I may modify the same within the scope of the appended claims without departing from the spirit of my invention.

The calendar as shown includes a folder F having a front side f, a back f' which is integral with the front f, and intermediate bottom portion b, and end flaps e, e, which are bent rearwardly from the front and attached to the back for inclosing the adjustable members, carried within the folder. Staples 1, 1 are provided at the top and

near the corners, and extend through the front f and back f' , and other staples 2, 2, near the lower edge of the folder, and 3, 3, which are vertically aligned with the staples 5 2, 2 and spaced substantially therefrom, serve to hold the folder together. A rectangular opening O is provided in the front f of the folder and a scale of characters S is provided at the top edge of said 10 opening and extends from the center of the opening to the right edge thereof, lines being provided in the scale which project downwardly from the characters to the edge of the opening for purposes hereinafter described. A cord F' is suitably attached to the top of the folder F for the purpose of suspending the calendar from a hook or for carrying it about, as may be desired.

In the center of the front f of the folder 20 and near the top thereof, I provide an opening having a horizontal portion f^1 with a reduced portion f^2 thereabove, and a vertical portion f^3 extending downwardly from the portion f^1 ; a guide line L is printed or 25 marked on the face f of the folder and extends from the top edge of the opening f^2 to the upper edge of the face f of the folder and serves to indicate the proper position of the adjustable members of the calendar 30 as hereinafter described. The opening f^3 is for the purpose of displaying the index characters for establishing the relation of the index of the week to the index of the month, as hereinafter described. The name of any 35 month succeeding the month shown in the opening f^1 is adapted to be displayed through an opening f^4 in the center and near the bottom of the front f of the folder.

A card C of rectangular form is provided 40 within the folder and stationarily held therein by means of the rivets 3, 3 which extend through apertures 3', 3' formed in the member C and the rivets 2, 2 extending through apertures 2', 2' therein. Rivets 1, 1 at 45 the bottom of the folder extend through apertures 1', 1' and a rivet 4 extends through an opening 4' midway between the ends of and slightly above the horizontal center of the card in the central portion of 50 the member C. I provide a schedule of dates S' peculiarly arranged in sequence for the purpose of my invention. This schedule is substantially elongated as compared with the ordinary schedule of dates in a calendar 55 month and consists of six horizontal columns of numerals and thirteen vertical columns of numerals, the right hand portion of the said schedule which includes the last seven vertical columns is typical of a calendar month in 60 which the first day of the month falls on Sunday, and the left hand portion of said schedule including the first seven columns thereof is typical of a calendar month in 65 which the first day of the month falls on Saturday. The two portions are so con-

nected in a single schedule that the sequence of the numbers for either the right or left hand portion thereof is preserved and also so that the overlapping numerals which are found in the central column may be used 70 with either the right or left hand schedules. An elongated opening 5 is provided below the schedule of dates S' on member C and is adapted to register with the opening f^4 in the front of the folder F when member 75 C is properly positioned within the folder.

This member C is for the purpose of indicating the days and arrangement of any selected or current month, and the proper number of vertical columns of the numerals 80 on the scale S' thereon is adapted to be displayed through a rectangular opening 6 in a weekly guide card W which is rectangular in form and is slidably held adjacent to the front f of and within the folder for movement over the face of the card C. This index or guide member W has slots 7, 7 and 8, 8 at the bottom which are adapted to engage respectively the rivets 3, 3 and 2, 2 in the folder, and the card may be moved 85 horizontally in the folder by means of a tab 9 on the right hand edge of the opening 6 thereof. A scale S² of characters having the names of the days of the week thereon, is provided adjacent to the top edge of the 90 opening 6 and said opening is of a width corresponding to that of seven of the vertical columns on the scale S¹ of member C.

It will be thus apparent that the member W is so held in the folder that the opening 6 100 therein will at all times be within the opening O of the front f of the folder, and, as stated, the schedule S¹ of member C is centrally disposed relative to the opening O in the folder and the width of said opening is 105 substantially equal to that of the schedule S¹ on member C.

A card C' is slidably held within the folder on the rivets 2, 2 and has slots 9, 9, 110 formed near the lower edge thereof for receiving said rivets. A tab 10 is provided near the left hand end of said member C' and is adapted to be bent at right angles to the face of said member, and extended through an elongated slot f^5 at the lower left hand portion of the front f of the folder, as 115 shown in Fig. 1. A schedule of dates S² is provided on the member C' and the arrangement of the numerals thereof is substantially similar to that on the member C, with the exception that two additional columns are 120 provided on the left hand end of the scale. The upper edge of member C' is cut away at 11 and 12 as shown in Figs. 1 and 5, so as to provide vertical edges at the ends of the 125 cuts which are adapted to register with the lines between the columns of numerals on the card C for the purpose of obscuring the superfluous numbers on the scale S¹.

Thus, it will be understood that when 130

there are only thirty days in a current month, the card C' would be moved over the card C so that the edge of the cut 11 would obscure the number "31" on the scale S¹.
 5 The schedule S² on card C' will preferably have the numbers thereon in red or a different color from the numbers on the scale S¹ of card C; the schedule S² is being provided for the purpose of indicating the calendars
 10 for the month succeeding the current or any selected month, shown on card C. Member C', as shown in Fig. 1, is mounted within the folder adjacent to the front face of card C and is adapted to be moved thereover for
 15 the purpose stated.

Intermediate the weekly index member W and the subsequent month card C' I provide a movable strip C'' which has slots 13, 13 near the lower edge thereof adapted to receive the rivets 2, 2, and has a tab 14 thereon which is adapted to be bent outwardly therefrom and extends through an elongated slot f⁷ in the face of the front sheet f of the folder, as shown in Fig. 1. The upper portion of member C'' has cuts 11' and 12' therein with vertical edges at the end of the cuts for the purpose of obscuring the superfluous dates in the subsequent month calendar schedule S² of member C'.

30 The operation and use of the member C' relative to member C and of the member C'' relative to the member C' is similar, and the length of the cuts 11 and 12 of the member C' and 11' and 12' of member C'' is such that when properly moved over the schedules S¹ and S² respectively, the superfluous numbers will be covered by the right hand portions of said members.

The front f of the folder has a scale of
 40 numbers "1, 2, 3 and 4," designated as f⁶, above the cut f⁵ in the left hand portion thereof, with lines leading from said characters downwardly to the edge of the slot f⁵. The tab 10 of member C', by means of which
 45 said member is moved in the folder, has a guide line 15 thereon which is adapted to register with the lines depending from the numerals "1, 2, 3 and 4" adjacent to the slot f⁵ so as to indicate the proper positions
 50 in the folder for the member C'. The numbers "1, 2, 3 and 4" opposite the slot f⁵ constitute an index for establishing a proper relation between the days of the current month and the days of the succeeding month.
 55 For instance, the number "1" may indicate twenty-eight days in a month, number "2" twenty-nine days in a month, number "3" thirty days in a month, and number "4" thirty-one days in a month. If, therefore,
 60 the month succeeding any selected month shown on the card C is to be February, and February in that particular year has twenty-eight days, the card C' would be moved to the left by means of the tab 10 so that the
 65 line 15 on said tab will register with the line

opposite the numeral "1" and the members C and C' may be brought into proper relation for any other months by similar movement of the member C' relative to the member C, depending upon the extent of such movement as gauged by the index just described.

Member C'' is similarly adjustable relative to the member C' by means of the tab 14 in the slot f⁷ of the folder, and a scale of
 75 characters f⁸ is provided above the said slot and includes the characters "X, Y, O, Z" and graduations in the scale f⁸ extending from the characters to the edge of the slot f⁷, line 16 being provided on the tab 14 for registration therewith.

The characters "X, Y, O, Z" of the scale f⁸ are arbitrarily selected and correspond to the numerals "1, 2, 3 and 4" of the scale f⁶, and more particular reference to and description of both of these scales will be hereinafter made. An index Y and a month index M are commonly and concentrically pivoted within the folder on the rivet 4, openings 17 and 18 being provided respectively in said members for receiving said rivets. The diameter of said members is such that portions thereof will project above the top edge of the folder F and one of said members, preferably the member M, may be
 95 slightly smaller in diameter than the member Y, both of said members being circular in form. Member M has a plurality of elongated openings 19, 19, etc., equally spaced apart and concentrically formed therein, the names of the months of the year are provided in duplicate on the front face of member M, and in sequence therearound, so that they will be visible through the openings f¹ and f⁴ in the front f of the folder, as shown
 100 in Fig. 1.

The inner series of months on member M is for use in connection with the current calendar, and the outer series, the printing of which is inverted with respect to the inner series, is for the use in connection with the subsequent calendar month. Thus, as shown in Fig. 1, the month of "December" being indicated on the member M through the opening f¹ for the current month, the month of "January" on the outer series of months will be indicated through the opening f⁴ on the folder. The arrangement of the names of the months on said member is such that the proper month will at all times be visible
 110 through the openings f¹ and f⁴, and the names of the month, as shown, are printed on opposite sides of the openings 19 which are provided so as to render the names of the year visible therethrough.

The year calendar member Y may have any number of years printed thereon near its periphery but preferably a complete cycle of twenty-eight years, designated, as shown at 20, 20, etc. The year designations are
 125 130

equally spaced apart and arranged in a concentric circle relative to the center of the disc and a column of characters including the characters A, B, C, D, E, F, G, shown 5 on the scale S of the folder and combined with the numbers "1, 2, 3, and 4" of the scale f^6 and the characters "X, Y, O, Z" of the characters f^8 are provided on the member Y and are arranged in radial formation 10 inwardly of the year designations, as shown in Fig. 8. The arrangement of these index characters is such that there will also be circular columns and will be exposed to view through a series of openings 21, 21, etc., in 15 the member M which are arranged in an involute curve and on the radial lines of the openings 19. The openings 21 also have one or the other of the numerals "1, 2, 3, and 4" of scale f^6 adjacent thereto. Thus, as shown 20 in Fig. 1 through the openings f^1 , the numeral "4" of the scale f^6 opposite the opening 21 on the radial line of the month of "December" of the inner series may be seen 25 through the opening f^3 and the character "D" of the scale S on the radial line of the year 1920 on the member Y may be seen through the opening 21 of the member M. Also, one of the characters "X, Y, O, Z" may appear either on the member M opposite the opening 21 or on the scale of characters of member Y as the case may be, for 30 obtaining the proper combination between the members C, C', C'', M, W and Y.

As shown in Fig. 1 the current month of 35 "December," 1920 is indicated by the card C while the subsequent month of "January," 1921 is indicated on the card C' and the proper combination is effected by moving the member C' so that the line 15 on the tab 40 10 thereof will register with the character "4" of the scale f^6 and by further moving the weekly index W so that the line 22 thereon will register with the character "D" of the scale S and by further moving the member C'' so that the line 16 on the tab 45 14 thereof will register with the character "D" of the scale f^8 .

The years will be indicated and visible 50 through the opening f^2 in the front f of the folder and also through the openings 19 on member M.

In some cases only two characters of the scales S, f^6 , and f^8 may be shown. For instance, the index might read "3A," and in 55 such case the member C'' would be adjusted to the character "O" of the scale f^8 . The absence of the third character is occasioned by the fact that throughout the year there are only three combinations between consecutive months wherein a month consisting 60 of thirty or less days is not followed by a month consisting of thirty-one days, or in which a month consisting of thirty-one days is not followed by a month consisting of 65 thirty days. The exceptions above referred

to are the sequences January-February, July-August, December-January, and it is unnecessary to adjust the scale f^8 other than to leave it at "O" when any other sequence of months occurs.

70

The operation of my calendar is as follows:

It being desired to provide a calendar for any given month of any given year prior or subsequent to a current year, for instance 75 "January 1915," the year index card Y is rotated on its axis until the year "1915" appears through the opening f^2 in the front f of the folder, and also through the corresponding opening 19 of member M. When 80 moved into proper position a line 1" on member Y will register with the line 1 on the folder. The member M is then adjusted so that a line 1' will register with the lines 1 of the folder and 1" of the member Y, and 85 the month of "January" appears through the opening, f^1 in the front of the folder. When the members Y and M are thus adjusted, the index characters "B X" on member Y which appear in the 1915 column thereon will be visible through the opening 21 of member M which is radially alined with the month of "January" thereon, and the character "4" will appear at the left hand side of the opening 21.

90

Thus the index for this particular combination reads "4 B X." The card C' is then adjusted by means of the tab 10 to the character "4" of scale f^6 . The card W is then adjusted by means of the tab 9 thereon so that the line 22 will register with the character "B" of the scale S on the folder and the card "C" is adjusted so that the tab 14 thereon will register with the character "X" of the scale f^8 .

95

The adjustment of the members Y, M, W, C' and C'' in the manner stated thus brings into view that portion of the scale S¹ on member C which will represent a calendar for the month of January, 1915, and also that portion of the scale S² of card C' which will represent a calendar for the succeeding month of February. The name of the succeeding month "February" will be automatically moved into registration with the opening of f^4 in the folder below the calendar when the current month is shown.

100

In order to illustrate another operation, let it be assumed that it is desired to ascertain the name of the day after the 4th of July, 1910. In such case, member Y is adjusted as before, so that the year "1910" will appear at the top of the folder. Member M is adjusted as before so that the month of "July" will appear at the top of the folder in registration with the year 1910 and the month of "August" will appear at the bottom of the folder as the month subsequent to the month of July. In this particular case the index for adjusting the mem-

105

110

115

120

125

130

bers W, C' and C'' will appear through the portion f^s of the opening in the folder and will be seen to be "4BZ." Member C'' is then adjusted to the numeral "4" of the 5 scale f^s , member W is adjusted to the character "B" of the scale S of the folder and member C' is adjusted to the character "Z" of the scale f^s . Thus, the calendar for "July" and "August" 1910 will be provided 10 on the cards C and C' respectively, and by reference to the calendar for "July" it will be found that July the 4th fell on Monday, and, therefore, the day following fell on Tuesday.

15 In order that Sundays on my improved calendar may be indicated differently from the other days of the week, I may provide a thin transparent strip at the left hand edge of the opening 6 in the member W of 20 colored material, such as celluloid, so as to cover the numerals on the card C and C' in the Sunday column, as indicated in Fig. 6.

It will be readily apparent that I have 25 provided a convenient, compact, economical and comprehensive calendar capable of ready manipulation for ascertaining any 30 dates within the range of a particular calendar, and possessing beneficial characteristics which will be readily apparent to users of such calendars.

What I claim is:

1. A calendar comprising relatively stationary and movable members having the days of the month printed thereon in columnar formation, the columns of days on one of said members being in registration with the columns of days on the other member, and a relatively movable member having an opening therein for exposing 40 seven columns on each of said members to view simultaneously, indicia printed at the top of said opening and registering with said columns, for indicating the days of the week.

45 2. A calendar including relatively stationary and movable members having numerals thereon representing the days of the month and arranged in columns of weeks, said columns of weeks on one of said members registering with the columns on the other member, a relatively movable member common to said other members having indicia thereon representing the days of the week and adapted to register with said 50 columns of numerals, and a member having two series of names of the months adjustably supported thereon for association with said other members for simultaneously indicating the names of and calendars for two consecutive months.

60 3. A calendar including relatively stationary and movable members having numerals thereon representing the days of the month and arranged in columns of weeks, 65 a relatively movable member common to

said other members having indicia thereon representing the days of the week and adapted to register with said columns of numerals, a member having two series of names of the months adjustably supported 70 thereon for association with said other members for simultaneously indicating the names of and calendars for two consecutive months, and a member having year designations printed thereon and adapted to be 75 adjusted for rendering selected years visible with said monthly calendars.

4. A calendar including relatively stationary and movable members having numerals thereon representing the days of the month and arranged in columns of weeks, a relatively movable member common to said other members having indicia thereon representing the days of the week and adapted to register with said columns of numerals, a 80 member having two series of names of the months adjustably supported thereon for simultaneously indicating the names of and calendars for two consecutive months, and a member having year designations printed 85 thereon and adapted to be adjusted for rendering selected years visible with said monthly calendars, said year designating member having columns of index characters thereon whereby said other members may be 90 adjusted to correspond to a given year.

5. A calendar having relatively stationary and movable members with columns of numerals arranged thereon representing the days of the month, a relatively adjustable member having indicia thereon representing the days of the week and adapted for selective registration with said columns of numerals, on said stationary and movable members, an index scale for regulating the 100 adjustment of said last mentioned members, separate monthly and yearly designating members, and index scales for regulating the 105 relative adjustment of said first mentioned members, as described.

6. A calendar comprising a folder having an opening therein, an index member movably disposed over said opening and also having an opening therein, and provided with graduations for registration with index scales provided on said folder, relatively adjustable members adjacent said index member and having numerals thereon representing the days of two separate months, indicia being provided on said index member representing days of the week, adapted for registration with the column of days on said relatively adjustable members, and separately adjustable monthly and yearly indicating members adapted to display index characters for determining the adjustment of said other members, as described.

7. A calendar including a pair of relatively adjustable members having a multiple series of numerals representing days 130

- 6
- of the month indicated thereon in columnar formation by weeks, an index slide having days of the week thereon one of said members overlapping the other for obscuring the numerals representing superfluous days in a month, when said members are adjusted for given months, a month indicating member, as described. 65
8. A calendar including relatively adjustable members having days of the month indicated thereon in columnar formation by weeks, one of said members overlapping the other for obscuring the numerals representing superfluous days in a month, when said members are adjusted for given months, and a relatively adjustable index, member having indicia for the days of the week thereon, and said indicia being adapted to register with said columns of numerals for providing calendars for two consecutive months. 70
9. A calendar embodying relatively adjustable day units having the days of the month indicated thereon in numerical order by weeks, and an index member having the days of the week indicated thereon for registration with said numerals, a month unit adjustably supported for denominating the months indicated on said day units, a year unit adjustable relative to said other units for indicating the year, and a series of index scales including characters corresponding to characters provided on said month and year units and on said folder, for determining the extent of adjustment of said day units and said index member. 75
10. A calendar having relatively adjustable day indicating units with vertical columns of numerals thereon representing the days of the month, the number of such columns being in excess of the days of the week, an index member adjustable relative thereto and having the days of the week indicated thereon for registration with seven of said columns of numerals at one time, one of said day units overlapping said other unit and having cut away portions whereby the superfluous days in a month may be obscured when said units are adjusted for any two consecutive months. 80
11. A calendar having relatively adjustable day indicating units with vertical columns of numerals thereon representing the days of the month, the number of such columns being in excess of the days of the week, an index member adjustable relative thereto and having the days of the week indicated thereon for registration with seven of said columns of numerals at one time, one of said day units overlapping said other unit and having cut away portions whereby the superfluous days in a month may be obscured when said units are adjusted for any two consecutive months, and a separately adjustable guide member overlapping the other of said day units for obscuring superfluous days in a month, when so adjusted. 85
12. A calendar comprising relatively adjustable members having numerals thereon representing days of the month and arranged in vertical columns, the number of said columns being in excess of seven, an index member movable over said day indicating members, and having indicia thereon representing the days of the week for registration with said columns of numerals and an opening therein for exposing seven of said columns of numerals at one time, and an index for adjusting said members for exposing the numerals corresponding to the exact number of days in two consecutive months, and for establishing the proper relation between the days of the week and the days of the month. 90
13. A calendar comprising relatively adjustable members having numerals thereon representing days of the month and arranged in vertical columns, the number of said columns being in excess of seven, an index member movable over said day indicating members, and having indicia thereon representing the days of the week for registration with said columns of numerals, and an opening therein for exposing seven of said columns of numerals at one time, and an index for adjusting said members for exposing the numerals corresponding to the exact number of days in two consecutive months, and for establishing the proper relation between the days of the week and the days of the month, and month and year indicating means co-operating therewith for completing the calendar. 95
14. A calendar including separate day indicating members for two consecutive months, a relatively adjustable index member for exposing the proper numerals representing the exact number of days in said months and for indicating the days of the week thereof, a month indicator for simultaneously displaying the names of the two consecutive months, and a relatively adjustable year indicator for displaying the year. 100
15. A calendar having separate members for indicating days of the week and month, the month and year and including a year indicator having a group of year denominations thereon, a column of index characters aligned with each of said year denominations, similar characters being provided on the exterior of the calendar in the form of a scale, 105 and means for adjusting all of said members whereby the calendar for two consecutive months may be simultaneously displayed. 110
16. A calendar comprising separate days, month and year cards, said year card having a plurality of years denominated thereon, and a group of index characters for each of said years, a scale of characters on the ex- 115

terior of said calendar corresponding to said group of characters on said year card, said day indicating means including separate groups of numerals for two consecutive months, a scale of characters on the exterior of said calendar for regulating the relative adjustment of said day cards, and means for simultaneously denominating the consecutive months and indicating the combination of index characters for adjusting all of said members into proper relationship for providing a calendar for two selected consecutive months of a given year.

17. A calendar comprising a stationary card having numerals thereon representing the days of the month, a relatively movable card also having numerals thereon representing the days of the month, a relatively movable index card having an opening therein for exposing certain of the numerals on said stationary and movable cards, a scale for regulating the movement of said index card to denominate the days of the week on said stationary and movable cards, a scale for regulating the movement of said movable month card to correspond with the calendar on said stationary month card, a movable guide card for obscuring the superfluous days in a given month on said movable month card, a scale for regulating the movement thereof, said movable month card represented on said stationary month card when two consecutive months are displayed thereon, and duplex month indicating means for separately indicating the names of the consecutive months.

18. A calendar comprising a stationary card having numerals thereon representing the days of the month, a relatively movable card also having numerals thereon representing the days of the month, a relatively movable index card having an opening therein for exposing certain of the numerals on said stationary and movable cards, a scale for regu-

lating the movement of said index card to denominate the days of the week on said stationary and movable cards, a scale for regulating the movement of said movable month card to correspond with the calendar on said stationary month card, a movable guide card for obscuring the superfluous days in a given month on said movable month card, a scale for regulating the movement thereof, said movable month card being adapted to obscure the superfluous number of days in the month represented on said stationary month card when two consecutive months are displayed thereon, and duplex month indicating means for separately indicating the names of the consecutive months.

19. A calendar comprising a folder having an opening therein, a scale of characters being provided adjacent said opening, an index member movable over said opening and having the days of the week indicated thereon, and graduations for registration with selected points on said scale, relatively adjustable members having separate groups of numerals thereon representing the days of the month, an opening being provided in said index member for exposing the proper groups of numerals on each of said members for two consecutive months, a month indicating card for simultaneously denominating the two consecutive months, and a year indicating card having characters thereon corresponding to the scale on said folder, whereby when said year card is moved to a certain position the index characters for such months may be exposed to view for regulating the movement of said other members.

GEORGE W. FENIMORE.
